G. R. MARSICO,

SIGNAL

APPLICATION FILED JUNE 9, 1919. RENEWED AUG. 27, 1921.

1,393,897.

Patented Oct. 18, 1921.

UNITED STATES PATENT OFFICE.

GERARD R. MARSICO, OF BROOKLYN, NEW YORK, ASSIGNOR TO PURITON MANUFACTURING CORPORATION, OF BROOKLYN, NEW YORK, A CORPORATION OF NEW YORK.

SIGNAL.

1,393,897.

Specification of Letters Patent.

Patented Oct. 18, 1921.

Application filed June 9, 1919, Serial No. 302,740. Renewed August 27, 1921. Serial No. 496,162.

To all whom it may concern:

Be it known that I, GERARD R. MARSICO, citizen of the United States, and resident of Brooklyn, in the county of Kings and State 5 of New York, have invented certain new and useful Signals, of which the following is a specification.

This invention relates to signals and more particularly to an improved construction of 10 the form of my invention shown in my application Serial No. 242,445, filed June 28, 1918, and to a further development of the invention disclosed in a co-pending application executed by me May 20, 1919, 15 Serial No. 303,739.

In my co-pending application aforesaid use is made of a heavy rotor adapted through the provision of a novel form of clutch mechanism to revolve with considerable 20 force against the vibratory member of the signal so as to increase the number of pulsations and produce sound of greater amplitude and intensity. In my application executed May 20, 1919, use is made of a clutch 25 mechanism for effective driving engagement with a rotor and in the structure I provided means for eliminating considerable friction 30 between the clutch mechanism and the rotor so as to permit the latter to revolve for a long interval after driving power is supplied to the rotor.

In the form of the invention which I will thoroughly describe in proper detail I have broadly accomplished an exceedingly novel 35 and useful functioning of parts so as to entirely eliminate friction between the clutch mechanism and the rotor whereby to permit said rotor to revolve for a still longer interval after the application of driving force 40 thereto.

Aside from the better functioning of the instrumentalities in an elimination of friction between the clutch mechanism and the rotor, I have combined and arranged in new 45 combinations the parts constituting the clutch mechanism so as to make the same responsive respectively to clutching and releasing movements and for exerting great radial impingement of the clutch with a co- 50 acting clutch surface of said rotor.

The various important features will be particularly pointed out hereinafter in connection with a detailed description of a pre-

ferred embodiment of my invention which I have selected for illustration in the accompanying drawings, in which similar reference characters indicate corresponding parts in the several views.

In the drawings,

Figure 1 is a side view of the signal with parts broken away and parts in section.

Fig. 2 is a side view of the rotor and its support.

Fig. 3 is a side view of the hanger.

Fig. 4 is a section on line 4—4 of Fig. 3. 65

Fig. 5 is a side view of the clutch devices.

Fig. 6 is a perspective of the rotor and clutch support and the carrying axle of said support.

10 represents a suitable case having a resonator 11 and diaphragm 12, the latter having an anvil or wear piece 14. These parts I describe as one of many well-known arrangements wherein sound can be created by a vibratory member, and only to this extent 75 do I wish to be limited when describing the principal features of my invention.

Within the case is a bracket 15 carrying a fixed axle 16 on which a sleeve-like-support 17 is mounted to freely revolve. This support has extensions 18 and 19 and a pinion 20. A driving mechanism is employed for rotating the support 17, the same consisting of a gear wheel 21 suitably mounted on the bracket 15 and arranged in mesh with a rack segment 22. The segment rocks on a pin 23 carried by the bracket and extending through the bracket as an integral part of the segment is an actuating lever 24. A flexible actuating element 25 is also employed and connected with the rack segment. Said element is movable through the case 10 and is provided exteriorly thereof with a hand grip 26. I prefer this arrangement in that due to the rough usage to 95 which such signals are subjected there is possibility of the lever 24 being broken and the element is therefore provided as an emergency actuator. The bracket is provided with an arcuate slot 27 in which one 100 end of a spring 28 is slidable, said end having connection at 29 with the segment. An opposite terminal 30 of the spring is suitably connected at 31 with the bracket 15 so that the segment is normally held in the position 105 shown in Fig. 1.

A rotor 32 is received by the extension 18 of the support 17 so as to freely revolve thereon. It carries a striking surface 33 adapted to co-act with the anvil 14 to dis-
 5 turb or vibrate the diaphragm. In addition thereto it carries an annular clutch surface 34 adapted to co-act with movable clutch devices 35—35 carried by a hanger 36. The extension 19 of the support 17 is
 10 fitted in an opening 36¹ of corresponding form in the hanger 36. This fixes the hanger to revolve with the support as will be understood. The clutch devices 35—35 are
 15 slideable in guides 37 upstruck from the hanger.

The support 17 carries cams 38 which bear against the inner ends 39 of the clutch devices. A spring 40 carried by the hanger has branches 41—41 which pass over tension
 20 pins 42 on the hanger and the free ends of said branches are extended into slots 43 in said clutch devices being normally in ne-
 25 gagement with the walls 44 of said slots to hold the clutch devices in neutral or inactive positions as shown in Fig. 1 of the drawing, the outer clutch faces 45 of said devices being spaced from the clutch surface 34 of the rotor.

An operation of the segment 29 in the di-
 30 rection of the arrow conveys motion in one direction to the support 17, causing the high sides of the cams 38 to move the clutch devices against the action of the spring branches 41, advancing the surfaces 45 in
 35 clutch impingement with said surface 34. The rotor then becomes fixed to the support 17 to revolve therewith during the entire period of actually expending the power ap-
 40 plied thereto but as soon as such power is released by the returning of the segment 22 it is evident that the support 17 again as-
 sumes its normal, relatively fixed position to permit the rotor to continue to revolve by inertia. The rapidity with which the
 45 clutch devices can be thrown into and out of driving engagement with the rotor and the fact that the surfaces 45 of said devices do not in any manner contact with the rotor when the latter is spending its force are
 50 points upon which I lay particular em-
 phasis. Quick action and reliable control of the parts is insured by the arrangements and combinations herein shown and de-
 55 scribed, while by eliminating material re-
 sistances between the respective clutch sur-
 faces the rotor is caused to revolve for a very appreciable interval.

While I have herein fully shown and de-
 60 scribed and have pointed out in the ap-
 pended claims certain novel features of con-
 struction, arrangement, and operation which characterize my invention, it will be under-
 65 stood by those skilled in the art that various omissions, substitutions, and changes in the forms, proportions, sizes, and details of the

device, of the materials used, and of their operation may be made without departing from my invention.

What I claim as new is:

1. In a device of the class described a vi-
 70 bratory member, a rotor co-acting with said member, said rotor having an annular clutch surface, a movable clutch element co-acting with said surface, a driven member, a device between the driven member and said element 75 for moving said element into driving en-
 gagement with said clutch surface, and a spring for normally holding the element out of contact with said surface.

2. A device of the class described com-
 80 prising a vibratory member, a rotor co-act-
 ing therewith, a driven member, said rotor having a clutch surface, a movable device between the driven member and the clutch surface for driving said rotor, said movable 85 device adapted to engage with said clutch surface to cause the rotor to move with the driven member when motion in one direc-
 90 tion is imparted to the latter, and a spring for normally holding said element out of engagement with said surface.

3. A device of the class described comprising a freely supported rotor having an annular clutch surface, a diaphragm co-acting with the rotor, driven clutch devices mov-
 95 ably positioned at diametrically opposite points of the annular clutch surface, means for normally holding said clutch devices out of engagement with the clutch surface, means for moving said devices against the 100 action of the holding means and into active engagement with said annular surface, and mechanism operable to revolve the clutch devices around the axis of the rotor when said devices are in engagement with said 105 rotor.

4. A device of the class described com-
 110 prising a vibratory member, a freely sup-
 ported rotor co-acting with said member to vibrate the same, a driven hanger, clutch devices carried by the hanger, said rotor having a surface adapted to co-act with the devices to permit the hanger and rotor to revolve together, means for moving said 115 clutch devices against said surface of the rotor, means for releasing the clutch devices from said surface to take the same entirely out of engagement therewith and enable the rotor to revolve by inertia while the hanger remains stationary, and means for 120 revolving the hanger.

5. A device of the class described com-
 125 prising a vibratory member, a freely sup-
 ported rotor co-acting with said member to vibrate the same, a driven hanger, clutch devices carried by the hanger, said rotor having a surface adapted to co-act with the devices to permit the hanger and rotor to revolve together, means for moving said 130 clutch devices against said surface of the

- 5 rotor, means for releasing the clutch devices from said surface to take the same entirely out of engagement therewith and enable the rotor to revolve by inertia while the hanger 10 remains stationary, and means for revolving the hanger, the releasing means consisting of a spring carried by the hanger and having end branches connected with said devices.
- 10 6. A device of the class described comprising a vibratory member, a supporting axle, a support adapted to revolve on said axle, a rotor co-acting with the member and free to revolve on the support, means for 15 revolving the support, a hanger fixed to the support, a clutch device carried by the hanger, the rotor having a clutch surface adapted to engage with said device, and means for establishing relative movements between 20 said surface and said clutch device when the hanger is revolved.
7. A device of the class described comprising a vibratory member, a fixed axle, a supporting member mounted to revolve on 25 the axle, a rotor free to revolve on the supporting member and provided with a clutch surface, a hanger carried by the supporting
- member and fixed thereto, a slidably mounted clutch device on said hanger co-acting with the clutch surface of the rotor, means 30 for revolving the support, means for sliding the clutch device in one direction, and means for sliding said clutch device in an opposite direction so as to position said device entirely out of engagement with the mentioned 35 clutch surface of the rotor.
8. A device of the class described comprising a vibratory member, a fixed axle, a rotor co-acting with said member, a revolving support on the axle on which the rotor 40 is mounted respectively for movements with and independent of said support, means for driving the support, a clutch device, a hanger fixed to the support and movably carrying the clutch device, a cam on the 45 support for moving the cam, and a portion on the rotor disposed in the path of movement of the cam for clutching engagement therewith.

Signed at Brooklyn, in the county of 50
Kings and State of New York, this 22 day
of May, A. D. 1919.

GERARD R. MARSICO.
